CLAIM

The ornamental design for a valve housing, as shown and described.

DESCRIPTION

FIG. 1 is a perspective view from the top-right of the valve housing;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a perspective view from the bottom-left thereof.

The features shown in broken lines are for the purpose of illustrating portions of the article that form no part of the claimed design.
